UNITED STATES PATENT OFFICE.

WILLIAM S. HUNKINS, OF LOS ANGELES, CALIFORNIA.

HOSE-SUPPORTER.

1,395,417.

Specification of Letters Patent.

Patented Nov. 1, 1921.

Application filed July 16, 1921. Serial No. 485,378.

To all whom it may concern:

Be it known that I, WILLIAM S. HUNKINS, a citizen of the United States of America, residing at Hollywood Station, Los Angeles, California, have invented a new and useful Hose-Supporter, of which the following is a specification.

My invention relates to a detachable connector particularly useful for securing elastic 10 hose supporter webbing to garments such as corsets and corset waists. For many reasons known to the trade, it is desirable to provide such means whereby whenever it becomes necessary to wash, launder, or iron a waist 15 or corset, the elastic webbing may be removed. To do this easily and advantageously, I have provided a simple and effective means of neat appearance which is always available for the above purpose, or for 20 permitting new or fresh elastic to be attached. Various other advantages will be apparent to anyone familiar with the needs in this art from a reading of the following description and an examination of the accompanying 25 drawings, in which,

Figure 1 is a front elevation (partly broken away) of the connection.

Fig. 2 is a front view of the connector with the tab and webbing removed and showing parts in a different position.

Fig. 3 is an edge view of the parts shown in Fig. 2.

Fig. 4 is a perspective view.

Figs. 5 and 6 are views of a modification. Referring first to the form shown in Figs. 1 and 4, 1 represents a tubular bushing which may be secured to a tab-end 2 in any suitable way. The connector link comprises preferably a loop of wire, one side 3 of which is unbroken. The other side is broken to form the two ends 5—5^a which are connected to the part 3 by the end bends 4—4^a. The bushing 1 is open at the top at one end for a slight distance for a purpose hereinafter described. The length of the loop relatively to the bushing is such that when it is in place the two ends cannot be pulled out by any independent longitudinal sliding movement until one end has first been disengaged. It

will be noted from Fig. 1 that when the parts are assembled the short end 5^a of the loop lies in that end of the bushing which has the top opening, and said short end may be disengaged from the bushing by lifting it upwardly. This may be most easily accomplished when the parts are turned at an

angle as shown in Fig. 3. The normal spring of the wire-loop serves to hold the short end normally seated in the bushing. When it is desired to detach the loop or connector link 60 from the bushing, that end of the tab-end 2 adjacent to the short end 5^a of the link is crowded back with the fingers so as to expose that end of the bushing. The link may then be swung into the position shown in Fig. 3, 65 and the short end 5^a may be lifted up free of the bushing and then swung to one side so as to clear the material of the tab-end surrounding said bushing whereupon the link may then be slid longitudinally so as to 70 withdraw the long end 5 from the bushing and thereby effect the disconnection.

If desired, a spring snap 1^a may be provided on the bushing adjacent to the opening in the top thereof which will serve to 75 frictionally prevent accidental upward disengagement of the short end 5^a of the loop from the bushing.

In the drawings, I have shown one end of a piece of elastic webbing 6 passed through 80 and around the loop and folded and stitched in place. Any other means of connection may be substituted.

Preferably the space between the upper and lower parts of the loop is so narrow that 85 the short end cannot be sprung out of engagement with the bushing excepting when the bushing and the loop are turned at an angle as indicated in Fig. 3, and this is of particular advantage in a connector of this 90 type, although I do not care to be limited thereto in all cases.

In the modification shown in Figs. 5—6, 11 represents the bushing which in this instance need not have an opening in the top at one 95 end. The link comprises a loop of wire, one side 13 of which is unbroken. The other side is broken to form the two ends 15—15^a which are connected to the part 13 by the end bends 14—14^a. The end 15 is preferably 100 longer than the end 15^a, and may be of a length corresponding substantially to the length of said bushing. The short end 15^a is preferably shaped so that it may be snapped over the end of the bushing when 105 the long end 15 is fully into place, the material of the tab being crowded back to permit the short end 15^a to be snapped into said bushing engaging position. In this case it is preferable to form a channel in the inner 110 side of the short end so that it will more effectively seat upon the end of the bushing

when in its operative position shown in Fig. 5.

Obviously in both forms when the parts are assembled and in operative position there can be no independent endwise movement sufficient to permit either end of the connector loop or link to be disengaged from the bushing.

Any suitable means may be provided for securing the connector to the tab end and the webbing. For example, the connector may be secured to the fabric by such a means as set forth in my former Patent No. 1,354,485 of October 5, 1920.

In both cases the fabric surrounding the bushing may serve to hold the short end of the link from being lifted out of the bushing excepting when said fabric is crowded back as above described.

What I claim is:

1. In a connector of the character described, a bushing, a loop having two free ends arranged to be engaged with said bushing, one end being longer than the other and insertible into said bushing by a longitudinal movement, the other end being engageable with said bushing by a lateral movement.

2. In a connector of the character described, a bushing, a loop having two free ends arranged to be engaged with said bush-

ing, one end being longer than the other and insertible into said bushing by a longitudinal movement, the other end being engageable with said bushing by a lateral movement, and means for yieldingly holding the last mentioned end of said loop in said operative position.

3. In a connector of the character described, a tubular bushing having a short opening in its top side at one end, a loop having two disconnected ends arranged to be engaged with said bushing, one end being longer than the other and insertible into said bushing by a longitudinal movement, the other end being engageable with said bushing by a lateral movement, said last mentioned end being short enough to permit it to be passed through said top opening in the act of assembling.

4. In a connector of the character described, a bushing, a loop having two free ends arranged to be engaged with said bushing, one end being longer than the other and insertible into said bushing by a longitudinal movement, the other end being engageable with said bushing by a lateral movement, a fabric surrounding said bushing and covering the same substantially from end to end.

WILLIAM S. HUNKINS.
